US0D1047564S

(12) **United States Design Patent** (10) **Patent No.:** **US D1,047,564 S**
(45) **Date of Patent:** **** Oct. 22, 2024**

(54) **VACUUM FLASK**

(71) Applicant: **ZOJIRUSHI CORPORATION**, Osaka (JP)

(72) Inventors: **Teruhisa Toyoda**, Osaka (JP); **Naoko Tatsukawa**, Osaka (JP)

(73) Assignee: **ZOJIRUSHI CORPORATION**, Osaka (JP)

(**) Term: **15 Years**

(21) Appl. No.: **29/806,783**

(22) Filed: **Sep. 7, 2021**

Related U.S. Application Data

(62) Division of application No. 35/510,074, filed on Feb. 5, 2020 (U.S. filing date under 35 U.S.C. 384), and having an international filing date of Feb. 5, 2020, now Pat. No. Des. 942,201.

(51) **LOC (14) Cl.** **07-01**

(52) **U.S. Cl.**

USPC **D7/319; D7/318**

(58) **Field of Classification Search**

USPC D7/300.1, 348, 350.1, 354, 362, 402, D7/509–511, 533, 601, 609, 611, 615, D7/619.1, 622, 649, 652, 653, 664, 671, D7/672, 674, 683, 691, 693, 698, 701, D7/703, 708, 319

CPC A47J 31/20; A47J 43/27; A47G 19/22; A21B 1/00; H05B 6/64

(57) **CLAIM**

The ornamental design for a vacuum flask as shown.

DESCRIPTION

FIG. 1 is a front perspective view of our new design;

FIG. 2 is a back perspective view thereof;

FIG. 3 is a front view thereof;

FIG. 4 is a back view thereof;

FIG. 5 is a top plan view thereof;

FIG. 6 is a bottom plan view thereof; and,

FIG. 7 is a right side view thereof, the left side view being a mirror image thereof.

1 Claim, 7 Drawing Sheets
